COOKING UTENSIL

Clyde C. Carr, Chicago, Ill., assignor to C. C.
Manufacturing Co., Chicago, Ill.

Application March 16, 1949, Serial No. 1,417

Term of patent 14 years

(Cl. D44—1)

To all whom it may concern:

Be it known that I, Clyde C. Carr, a citizen of the United States, residing at 4450 Ravenswood Avenue, Chicago, Illinois, in the county of Cook and State of Illinois, have invented a new, original, and ornamental Design for Cooking Utensil, of which the following is a specification, reference being had to the accompanying drawing, forming part thereof.

In the accompanying drawing, Figure 1 is a perspective view of a cooking utensil showing my new design; Figure 2 is a top plan view; Figures 3 and 4 are side elevational views taken at ninety degree intervals with respect to each other; and Figure 5 is a diametrical sectional view of the cover thereof.

The dominant features of my design reside in the handles, as shown.

I claim:

The ornamental design for a cooking utensil, as shown and described.

CLYDE C. CARR.
